UNITED STATES PATENT OFFICE.

JAMES HODGSON PIERCE, OF WEST BAY CITY, MICHIGAN.

DESIGN FOR A VALVE-CASING.

SPECIFICATION forming part of Design No. 22,865, dated October 31, 1893.

Application filed September 15, 1893. Serial No. 485,626. Term of patent 14 years.

To all whom it may concern:

Be it known that I, JAMES HODGSON PIERCE, a citizen of the United States, residing at West Bay City, in the county of Bay and State of Michigan, have invented and produced a new and original Design for Valve-Casings, of which the following is a specification.

Figure 1 is a side elevation of a valve casing showing my design. Fig. 2 is a cross section in line 2—2, Fig. 1. Fig. 3 is a bottom plan view of the valve casing.

Like letters of reference refer to like parts in the several figures.

15 The leading feature of my design consists in a flat bottom and lateral enlargements or bulges on both sides of the valve casing near one end thereof in connection with the usual hexagonal end portions and oblique or inclined top portion of a straightway valve casing.

A is the body of the valve casing which is mainly cylindrical in form between the hexagonal end portions *a* and which is surrounded by an inclined top portion *b*.

25 C represents the flat bottom of the casing arranged near one of the hexagonal end portions, and D D represent the lateral bulges or extensions connecting the flat bottom on both sides with the upper semi-cylindrical portion of that part of the casing, the rest of the casing being cylindrical.

30 What I claim is—

35 The design for a valve casing herein shown and described.

Witness my hand this 25th day of August, 1893.

JAMES HODGSON PIERCE.
